CARL ERIC ANDERSON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,348,684.

Specification of Letters Patent. Patented Aug. 3, 1920.

Application filed June 14, 1917. Serial No. 174,743.

To all whom it may concern:

Be it known that I, CARL ERIC ANDERSON, a citizen of the United States of America, and residing at Bridgeport, in the county 5 of Fairfield and State of Connecticut, have invented a certain new and useful Improvement in Electric Switches, of which the following is a specification.

My invention relates to electric switches 10 and the object of my invention is to provide a simple and efficient switch mechanism the operating parts of which may be economically manufactured from sheet metal and readily assembled without the use of rivets, 15 pivot pins, or the like.

Referring to the accompanying drawings

Figure 1 is a plan view of a switch in which my invention is embodied in one form.

20 Fig. 2 is a longitudinal section on the line 2—2 Fig. 1.

Fig. 3 is a longitudinal section on the line 3—3 Fig. 1.

25 Fig. 4 is an exploded perspective of various elements of the switch mechanism.

The switch here shown is of the push button type and comprises an insulating base 10 of cup shape, across the open face of which extends the carrying yoke 11, secured 30 in position by screw bolts 12 and 13 (Fig. 3) passing through extended ribs at opposite ends of the receptacle. Adjacent the tapped holes in the yoke which receive the screw bolts 12 and 13, are depressed teats 35 14 and 15, tapped at their inner ends to receive the securing screws by which the usual cover plate (not shown) is held in position above the switch. The inclined walls leading to the threaded portion of the 40 teats form guide ways for the entering ends of the cover-plate-securing screws and facilitate their proper location.

45 Depressed ledges 16, 17, 18, and 19 at the four corners of the receptacle are overlaid by the offset upper ends of the terminal plates 20, 21, 22 and 23, each of which carries not only a binding screw 24 but also a switch terminal 25 extending into the switch chamber. Closing the open face of 50 the switch chamber is a sheet of insulating paper or fiber 26, resting upon narrow ledges 27 on the opposite side walls of the base 10, and notched at 28 in register with rib 29 which prevents the displacement of

the cover piece. At its opposite ends the 55 cover sheet 26, is slotted at 30 to permit the passage therethrough of the push buttons 31 and 32, while the tongues 33, formed by these slots, are bent down into the switch chamber against the inner faces of the 60 terminal plates 20—23 and serve to prevent the entry of stray wire beards into the switch chamber.

The switch mechanism proper is mounted upon a frame 34, (Fig. 4) struck from 65 sheet metal and angled to shape, and comprising a pair of opposed standards united by base straps 35. Ears 36, formed on these straps, are tapped at 37 to receive the securing screws 38 and 39 which pass through 70 the base of the receptacle. Each standard comprises a pair of legs 40—41 between which works the bridge piece 42 of the switch bar, the throw of which is thus limited. An outwardly extending lug 43 on each 75 standard is curved to form a trunnion on which the switch bar is supported, while above the trunnions 43 the standards are notched at 44 to afford bearings for the rocker 45.

80 The switch bar in the form here shown, comprises a blade 46 integral with the bridge piece 42, and an opposed arm 47 to which a second blade 48 is secured by insulating bushings 49 so that the blades 46 and 48 are 85 electrically independent of each other. The construction of the blades may be modified as may be desired and in certain instances, as for instance in a 3-point switch, both blades may be integral with the bridge piece. 90 In order to facilitate the mounting of the switch bar upon the frame, its legs are spaced sufficiently apart to straddle the frame and are shouldered at 50 and slotted at 51 so that it may be assembled on the 95 frame by merely passing the bar across the frame in such position that the trunnions 43 slide beneath the shoulders 50 and are seated in the upper ends of the slot bearings 51.

100 The rocker 45 is struck from sheet metal and comprises a pair of opposed plates united by a bridge piece 52. Outwardly offset bearing lugs 53 on the plates rest in the notches 44 formed in the upper portions of the frame standards. At opposite ends of 105 each plate, notches 54 are formed to receive the T-arms of the push plates 55 which are molded in the push buttons 31 and 32.

These T-arms are of sufficient width to project through the rocker bar plates and rest upon the shoulders 56 of the frame which form stops limiting the throw of the rocker bar in opposite directions.

5 The switch spring 57 which extends between the rocker bar and the switch bar, surrounds a guide pin composed of two independent straps 58 provided at one end with 10 registering cross arms 59 against which one end of the spring abuts and adjacent to which are the projecting ends 60 which enter the slot 61 in the bridge piece 42 of the switch bar. At the opposite ends of the 15 straps 58 the latter are offset toward each other, as at 62, and serve to confine the bridge piece 52 of the rocker bar 45 which, in assembled position, lies between the straps 58 and bears against a washer 63 forming 20 an abutment for one end of the spring. If desired, a similar washer 64 may be provided at the opposite end of the straps to hold the latter together and afford an abutment for the corresponding end of the 25 switch spring.

The switch operates in readily understood manner. Upon depression of the "out" push button 31, the bar 45 rocks on its trunnions 53, and its bridge piece 52 moves toward the 30 bridge piece 42 of the switch bar, thereby further compressing the switch spring 57. When the bridge piece 52 of the rocker has passed to the opposite side of the axis of oscillation of the switch bar on its trunnion 35 bearings 43, the thrust of the switch spring forces the switch bar bridge 42 to move from its "off" stop position against the legs 41 of the frame to its opposite "on" stop position against the legs 40 of the frame, in which 40 position the switch blades 46-48 are in engagement with the switch terminals 25. The return to "off" position is obviously the reverse of this movement and is occasioned by the depression of the button 32 which now 45 occupies its "out" position.

It is obvious that by suitable changes in the construction of the switch bar 42 and rearrangement of the terminal plates, the switch connections may be variously modified, without altering the operation of the mechanism to which the invention relates. Both the switch blades may be insulated from the bridge piece which carries them. Other variations will readily occur to those skilled in the art, which do not depart from what I claim as my invention.

I claim:

1. In an electric switch, a frame comprising a pair of standards spaced apart and notched in register at their upper edges to form open bearings, and having therebelow alined bosses forming trunnions, in combination with a rocker pivoted in said open bearings and a switch bar pivoted on said 60 trunnions, a switch spring operatively in-

terposed between the rocker and switch bar and having an associated guide seated at one end against the switch bar and in sliding engagement at its other end with the rocker, together with means for oscillating the 70 rocker to shift the end of the switch spring engaged thereby from one side to the other of the axis of oscillation of the switch bar.

2. In an electric switch, a frame comprising a pair of standards spaced apart and recessed in register to form notch bearings and having alined bosses forming bearing trunnions in combination with a rocker and a switch bar respectively pivoted in said bearings, one of said pivoted members straddling the standards and the other lying between the same together with the switch spring operatively interposed between the rocker and switch bar, and means for oscillating the rocker to shift one end of the 75 switch spring from one to the other side of the axis of oscillation of the switch bar to operate the latter.

3. In an electric switch a frame comprising a pair of standards spaced apart and recessed in register to form notch bearings and having alined bosses forming bearing trunnions, each of said standards having a pair of legs, in combination with a rocker and a switch bar respectively pivoted on 95 said bearings, one of said pivoted members straddling the standards and working between the legs thereof, a switch spring operatively interposed between said rocker and switch bar and means for oscillating 100 said rocker to shift one end of the switch spring from one to the other side of the axis of oscillation of the switch bar to operate the switch.

4. In an electric switch, a frame comprising integral sheet metal standards spaced apart and recessed in register to form notch bearings and having alined flanges curved to form bearing trunnions, substantially as described.

5. In an electric switch, a frame comprising integral sheet metal shouldered standards spaced apart, each standard having a pair of legs, said standards being recessed in register to form notch bearings, and having alined flanges forming trunnions, together with a member pivoted in said notch bearings and having its extent of oscillation limited by the shoulders on the standards and a second member pivoted on the trunnions and working between the legs of the standards which in turn limit the extent of its oscillation, substantially as described.

6. In an electric switch, a shouldered frame, a rocker pivoted thereon, a push button, a push plate carried thereby and having T-arms engaging the rocker and impinging against the shoulder on the frame to limit the extent of the oscillation of the rocker.

7. In an electric switch, a frame comprising a pair of spaced, shouldered, standards, a rocker pivoted on said frame and working between said standards, in combination 5 with a push button having a push plate with cross arms engaging said rocker and extending beyond the same into position to impinge against the shoulders of the standards to limit the throw of the rocker, substantially as described.

8. In an electric switch, a cup shaped insulating body, terminal straps arranged in the corners of the switch chamber, a switch mechanism within the chamber, push buttons for operating the same in combination 15 with a cover sheet of flexible insulation overlying the switch mechanism and resting on the sides of the insulating body, said sheet being slotted to afford freeways for the push buttons and the arms formed by said slots being curved downward into the chamber 20

opposite the terminal straps to prevent the entry of foreign bodies into the switch chamber.

9. In an electric switch, a pivoted element 25 comprising opposed members having corresponding offset portions and offsetting shoulders and open bearings therein extending through the offsetting shoulders.

10. In an electric switch a pivoted element 30 comprising opposed members having corresponding offset portions and offsetting shoulders and open bearings therein extending through the offsetting shoulders, together with a switch frame having trunnions over which said shoulders may freely 35 pass to bring the open bearings to rest upon said trunnions.

In testimony whereof I have signed my name to this specification.

CARL ERIC ANDERSON.
